US00D744967S

(12) **United States Design Patent**
Krishnan et al.

(10) **Patent No.:** **US D744,967 S**
(45) **Date of Patent:** **** Dec. 8, 2015**

(54) **SPINDLE KEY**

(71) Applicant: **Veeco Instruments Inc.**, Plainview, NY (US)

(72) Inventors: **Sandeep Krishnan**, Princeton, NJ (US); **Keng Moy**, Basking Ridge, NJ (US); **Alexander I. Gurary**, Bridgewater, NJ (US); **Matthew King**, Montville, NJ (US); **Vadim Boguslavskiy**, Princeton, NJ (US); **Steven Krommenhoek**, Annandale, NJ (US)

(73) Assignee: **Veeco Instruments Inc.**, Plainview, NY (US)

(**) Term: **14 Years**

(21) Appl. No.: **29/499,058**

(22) Filed: **Aug. 11, 2014**

(57) **CLAIM**

The ornamental design for a spindle key, as shown and described.

DESCRIPTION

FIG. 1 is a top perspective view of a spindle key showing our new design;

FIG. 2 is a left side view thereof, the right side view being a mirror image of the left side view;

FIG. 3 is a front view thereof;

FIG. 4 is a rear view thereof;

FIG. 5 is a top plan view thereof; and,

FIG. 6 is a bottom plan view thereof.

The broken lines shown in the drawings represent portions of the spindle key that form no part of the claimed design.

1 Claim, 2 Drawing Sheets
